US0D1096469S

(12) **United States Design Patent** (10) **Patent No.:** **US D1,096,469 S**
(45) **Date of Patent:** **** Oct. 7, 2025**

(54) **VALVE RECEIVER**

(71) Applicant: **Hunter Industries, Inc.**, San Marcos, CA (US)

(72) Inventor: **Michael F. Paul**, San Diego, CA (US)

(73) Assignee: **Hunter Industries, Inc.**, San Marcos, CA (US)

(**) Term: **15 Years**

(21) Appl. No.: **29/880,263**

(22) Filed: **Jul. 19, 2023**

(51) **LOC (15) Cl.** **10-04**

(52) **U.S. Cl.**

USPC **D23/235**; D10/96
